(57) **CLAIM**

The ornamental design for a dust pan, as shown and described.

DESCRIPTION

FIG. 1 is a top perspective view of a dust pan; FIG. 2 is a bottom perspective view of the dust pan of FIG. 1;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a left side elevational view thereof.

A right side elevational view is not shown because it is a mirror image of the left side elevational view shown in FIG. 7.

The ornamental design which is claimed is shown in solid lines in the drawings. The portion depicted in broken lines forms no part of the claimed design.
